ATTORNEYS

UNITED STATES PATENT OFFICE.

DANIEL HARRISON BAUMGARDNER, OF BROOKVILLE, PENNSYLVANIA.

DESIGN FOR A HOE.

SPECIFICATION forming part of Design No. 31,633, dated October 10, 1899.

Application filed August 24, 1899. Serial No. 728,374. Term of patent 14 years.

To all whom it may concern:

Be it known that I, DANIEL HARRISON BAUMGARDNER, a citizen of the United States, residing at Brookville, in the county of Jefferson and State of Pennsylvania, have invented and produced a new and original Design for a Hoe, of which the following is a specification, reference being had to the accompanying drawings, forming a part thereof, in which—

Figure 1 is a perspective view of a hoe embodying the features of my design, and Fig. 2 is a central vertical section through the same.

The feature of the design consists in the form of the body or blade A of the hoe, the edge whereof is provided with an upper cen-

tral depression, while the side edges are oppositely convexed from said depression, meeting at the lower central portion of the body, forming a point. A shank B, which extends from the upper central depression, is upwardly and rearwardly curved therefrom, and the rear or body portion of the shank B is straight and the rear terminal of the said shank is pointed.

I claim—

The design for a hoe herein shown and described.

DANIEL HARRISON BAUMGARDNER.
